2 SHEETS-SHEET 2.

Inventor

JACOB H. JACOB.

UNITED STATES PATENT OFFICE.

JACOB H. JACOB, OF PEORIA, ILLINOIS.

SELF-LEVELING TABLE AND CHAIR.

1,015,230.

Specification of Letters Patent. Patented Jan. 16, 1912.

Application filed March 20, 1911. Serial No. 615,618.

To all whom it may concern:

Be it known that I, JACOB H. JACOB, a citizen of the United States of America, residing at Peoria, in the county of Peoria and State of Illinois, have invented certain new and useful Improvements in Self-Leveling Tables and Chairs, of which the following is a specification, reference being had therein to the accompanying drawing.

My invention relates to improvements in self-leveling tables and chairs, and has for its object to provide such an apparatus, which can be used on vessels and other conveyances and which will at all times maintain the tables and chairs level and in their proper relative position with respect to each other.

Other objects and advantages of my invention will appear in the course of the following specification.

In the accompanying drawings: Figure 1 is a side elevation, partly in section, of a table and chairs therefor constructed and arranged in accordance with my invention. Fig. 2 is a perspective view of the stand employed to support the table and chairs. Fig. 3 is a perspective view of the standard and weight employed to maintain the table and chairs level. Fig. 4 is a perspective view of the plate connected to the underside of the table, together with the end portions of the chair supporting beams which are supported therefrom. Fig. 5 is a plan view of the collar and the end portions of the chair beams connected thereto, together with the cross pieces connecting them. Fig. 6 is a perspective view of one of the supports constituting the socket.

Referring to the drawings, which illustrate the preferred embodiment of my invention, 1 designates the table about the outer edge of which is arranged an upstanding ledge 2. Secured centrally to the underside of the table is a square plate 3 for a purpose to be hereinafter described. The table is supported by means of a stand 4, which comprises oppositely-disposed corresponding sections 5. Each section 5 comprises a pair of outwardly and oppositely inclined legs 6, which terminate in feet 7 provided with apertures 8, through which are passed screws 8^a adapted to enter registering apertures in plates 9, which are set in flush with the floor on which the table is supported, to secure the feet. Each leg 6 of each section 5, at its upper end, is deflected angularly and extended

upwardly and inwardly toward each other to form arms 10. The arms 10 of each section 5 support a semi-circular support 11 which is provided with a horizontally arranged groove 12 which is preferably located below the middle of the support. At each end of each semi-circular support 11 is a lug or projection 13, which is provided with a centrally located aperture 14. As illustrated, the semi-circular supports 11 are adapted to be secured together by bolts 15 passing through the registering apertures 14 in the lugs 13 to form a circular socket or bearing 16 having an internal continuous circular groove 12^a formed by the meeting of the ends of the grooves 12. In order to brace and firmly hold the sections 5 together, a band 17 is riveted or otherwise suitably secured to the arms 6 near their upper ends. In the circular groove 12^a in the socket or bearing 16 are positioned a plurality of balls 18, and positioned in the socket and adapted to bear on the balls 18 is a large ball 19 axially of which, from the top and bottom thereof, is respectively a short upstanding rod 20 and a relatively long depending rod 21. At the lower end of the depending rod is a large, heavy ball 21^a, which serves as a weight to keep the rod 21 vertical and thereby maintain the table and chairs level no matter what the inclination of the floor above which they are supported may be. The upper end of the rod 20 is provided with four outwardly and upwardly extending arms 22, which are angularly disposed with respect to each other and which terminate in feet 23, which are suitably secured to the plate 3 to support the table 1.

Positioned between the ball 19 and the outwardly extending arms 22 is a preferably integral circular collar or flange 24. Secured to the collar 24, at equi-distant points, are the inner ends of a plurality of outwardly-extending beams, each designated 25, which are spaced from the underside of the table. In order to further support the beams 25 a bolt or hanger 26 is passed through an aperture in each beam, and is threaded into a threaded aperture 27 in the plate 3, as shown. The apertures 27 are arranged one in each corner of the plate 3 and equidistant between said corners. The beams 25 are each extended horizontally with respect to the table until they reach a point near the outer edge of the table where they are curved downwardly to form U-shaped

portions 27'. The end of each U-shaped portion 27' terminates in four outwardly and upwardly-extending arms 28, which are angularly disposed with relation to each other and provided with fingers 29 which are secured to and support a chair 30. In front of each chair 30, in the U-shaped portion 27 is a cross-piece 31, which is attached centrally of its length to the beam 25 and at right angles thereto. Each cross piece, at each end, is furnished with an upstanding end piece 32, which projects above the top of the cross piece, as shown. The cross pieces serve as foot rests for the occupants of the chairs and the upstanding end pieces prevent the feet from slipping off the cross pieces. Each seat carrying beam 25 is furnished with a wire or rod brace 33, one end of which is connected to the plate 3 contiguous the bolt or hanger 26 supporting that particular beam, while the other end of said brace is connected to the beam in front of the U-shaped portion 27' thereof. Each beam 25 is further strengthened by a diagonal brace 34, which is connected at one end to the under side of the beam, just in front of the U-shaped portion 27', and at its other end in front of the cross piece 31. Between and intermediate the ends of each pair of beams 25 are transverse bars 35, the opposite ends of which transverse bars are connected to said beams and serve to maintain the beams in their relative angular positions.

35. What I claim is:

1. In an apparatus of the kind described, a vertical frame having a socket in its top, a rocking ball mounted in said socket, a stem depending from said ball, a weight on the lower end of said stem, an oscillating table

top mounted on said rocking ball, arms secured to and projecting beyond the sides of said table top, and a chair mounted on each of said arms.

2. In an apparatus of the kind described, a vertical frame having a socket in its top, a rocking ball located in said socket and having a depending stem, a weight on the lower end of said stem, a framework centrally mounted on said oscillating ball and having arms branching therefrom, each of said arms being of a bow shape at its outer end and having a foot rest, a chair on the outer end of each of said arms, and an oscillating table top mounted on said framework. 55

3. In an apparatus of the class described, a table, means for maintaining said table level, a collar carried by said means for maintaining said table level, a chair supporting beam spaced below the bottom of said table and connected at one end to said collar, a chair carried by said chair supporting beam, and a hanger adapted to support said chair-supporting beam in its spaced position. 60 65

4. In an apparatus of the class described, a table, means for maintaining said table level, angularly disposed chair supporting beams supported below said table, chairs carried by said chair supporting beams, and spacing members connected to said chair-supporting beams and adapted to maintain them in their relative angularly-disposed positions. 70

In testimony whereof I hereunto affix my signature in presence of two witnesses.

JACOB H. JACOB.
